PROPELLER GUARD FOR OUTBOARD MOTORS

Harry A. Sidney, Milwaukee, Wis.

Application June 15, 1946, Serial No. 677,029

11 Claims. (Cl. 115—42)

1

My invention relates to improvements in propeller guards for outboard motors.

The primary object of my invention is to provide a guard which will effectively cut and deflect weeds from the path of the propeller without materially retarding the motion of the boat with which it is associated.

Numerous attempts have heretofore been made to provide an effective guard for outboard motors, but so far as I am aware, none of the guards heretofore designed have been commercially successful because of their resistance to the motion of the boat, even in clear water, and the greatly increased resistance which they offer to the motion of the boat when in contact with weeds, and their tendency to be deflected by the weeds into contact with the propeller blades.

It is my object to overcome these objections and to provide a commercially successful guard for outboard motor propellers which will have knife-like cutter members capable of moving through the water with minimum resistance and will not become entangled in weeds, but will move with an effective shearing action against any obstacles in its path, whether comprising weeds or submerged tree branches, and in which the blades can have a minimum cross section and capability of instant adjustment to a raised position above the water line when the propeller is operating in water free of weeds.

In general, it is my object to provide a commercially successful weed guard applicable to all outboard motors without material impairment of their efficiency in propelling a boat, and without interference with steering operations.

In the following description, reference is had to the accompanying drawings, in which

Figure 1 is a side elevation of the lower portion of the shaft housing of an outboard motor and its propeller wheel, with my improved guard applied thereto.

Figure 2 is a front elevation of the same.

Figure 3 is a plan view of the lower portion of the guard, with its hanger bar shown in cross section, and a detached propeller wheel illustrated in its proper relation to the extremities of the weed guard fork arms.

Figure 4 is a detail cross section, drawn to line 4—4 of Figure 3.

Figure 5 is a view in side elevation, showing the guard in its elevated inoperative position, with dotted lines indicating an intermediate retracted position.

Figure 6 is a sectional view drawn to line 6—6 of Figure 1.

2

Like parts are identified by the same reference characters throughout the several views.

A knife-like hanger 10 is pivotally connected at 11 to an oscillatory bracket 12 associated with a clamping collar 13 which embraces the vertical shaft housing 14 of an outboard motor, preferably above normal water line. The hanger 10 is suspended in front of the housing 14 and has a sharp front edge 15 and therefore is adapted to move through the water with minimum resistance. Its lower end is forked to provide two divergent blade-like downwardly, outwardly, and rearwardly curving arms or blades 17 and 18, which have, respectively, knife-like edges 19 and 20 which face forwardly in their upper portions and laterally in their lower portions. The curvature of these blades is such that their sharp edges will move upon the weeds with a sliding or shearing action and cut them without materially retarding the motion of the boat. Also, in cutting the weeds, they will at the same time deflect the sheared portions laterally from the path of the propeller.

The rear margins of the hanger 10 and the fork arms 17 and 18 are preferably streamlined as indicated at 21, and the rear end portions of the fork blades are preferably in a substantially horizontal position at about the level of the axis of the propeller and sufficiently offset laterally to avoid danger of contact with the propeller wings 22. The free ends 23 of the blades 17 and 18 are located only slightly to the rear of the space in which the propeller wings rotate, whereby the slipstream will effectively carry the weed fragments away. I have found that if these forked blades are extended several inches to the rear of the propeller they interfere with this action of the slipstream and tend to induce eddies, which carry some of the fragments into contact with the propeller wings. A pair of resilient clips 25, located slightly above the cavitation plate 26, normally holds the hanger 10 in its working position.

But when released from these clips, the entire guard may be quickly adjusted to an inoperative position, either by unscrewing the thumb nut 27 from the clamping bolt 28 and detaching the clamping collar 13, or by swinging the hanger 10 to a raised inoperative position without disturbing the clamping collar 13. The bracket 12 provides one means for so adjusting the hanger 10 to a raised inoperative position.

It will be observed that the upper end portion of the hanger 10 is offset at 29 and the bracket 12 has a correspondingly offset pivot stud 31

which is socketed in the clamping collar and serves as an oscillatory pivot for the bracket, whereby the hanger may be swung past the housing 14 to the full line position in which it is shown in Figure 5. In either the raised position, or in the normal operative position, it may be locked by a removable pin 32.

When the propeller is to operate in clear water, the pin 32 may be removed to allow the bracket 12 to be oscillated on the collar 13. The hanger 10 may then be swung backwardly on its pivotal connection 11 to the position in which it is indicated by dotted lines in Figure 5, whereupon it may be swung laterally and upwardly to the position in which it is indicated in full lines in Figure 5. The hanger 10 then rests on a stop 35 which holds it in said raised position. The bracket 12 will have been rotated 180°, and the stud or stem 31 may then be again locked to the bracket 13 by reinserting the locking pin 32.

The hanger blade 10 and its knife-like fork arms 17 and 18 are relatively wide in proportion to their thickness. This not only enables them to cut through weeds and water freely, but their relative width as compared with their thickness prevents them from being bent or deflected in the direction of the propeller.

I claim:

1. A weed guard for an outboard motor having a propeller and an upwardly extending housing member for a propeller driving shaft, comprising the combination with said housing member, of a hanger connected therewith normally in a guarding position in front of the housing, and provided with fork arms diverging from the end of the hanger distant from said pivotal connection laterally, downwardly and rearwardly on opposite sides of the propeller, said fork arms having sharp weed cutting edges.

2. A weed guard as set forth in claim 1, in which the hanger comprises a blade with a sharp front cutting edge.

3. A weed guard as set forth in claim 1, in which means are provided whereby the guard may be quickly adjusted to an inoperative position when the propeller is operating in water free of weeds.

4. A weed guard as set forth in claim 1, in which means are provided for adjusting the hanger into and out of its normal guarding position to a raised inoperative position.

5. A propeller guard for an outboard motor, comprising the combination with the shaft housing of an outboard motor of a hanger having its upper end portion pivotally supported in front of said shaft housing, said hanger having a sharp weed-cutting front edge, and depending blade-like fork arms extending downwardly, laterally and rearwardly from the lower end of the hanger and provided with sharp weed-cutting edges at their front and laterally facing margins.

6. A propeller guard for an outboard motor, comprising the combination with the shaft housing of an outboard motor of a hanger having its upper end portion pivotally supported in front of said shaft housing, said hanger having a sharp weed-cutting front edge, and depending blade-like fork arms extending downwardly, laterally and

rearwardly from the lower end of the hanger and provided with cutting edges at their front and laterally facing margins, the free extremities of said fork arms being located at the respective sides of the path of the propeller and slightly to the rear of the space in which the propeller revolves.

7. A weed guard for an outboard motor, comprising a hanger member provided with means for supporting it in front of the propeller shaft housing of an outboard motor, and divergent blades connected with said hanger and extending from the lower end thereof downwardly, laterally and rearwardly in positions for guarding the path of a propeller associated with the housing in front of which the hanger is supported, said blades having forwardly directed cutting edges.

8. A weed guard for an outboard motor, comprising the combination of a clamping collar adapted to embrace the vertical shaft housing of an outboard motor, of a bladed hanger having its upper end connected with said collar and its lower end forked and extending in the form of downwardly and laterally divergent and rearwardly curving fork arms provided with cutting edges for contact with weeds in the path along which the motor advances.

9. In a combination as set forth in claim 8, an oscillatory bracket mounted on said collar, a pivotal connection between said bracket and hanger, and means for locking the bracket with the hanger either in working position or in a raised inoperative position.

10. A weed guard for an outboard motor comprising the combination with an outboard motor housing member, of a hanger pivotally connected with said housing member and adjustable thereon to either a raised inoperative position or a depending guarding position, the end of said hanger distant from said pivotal connection having divergent bladed fork arms adapted, when the hanger is in guarding position, to extend downwardly, outwardly and rearwardly on opposite sides of a propeller wheel associated with said outboard motor, said arms having weed cutting edges substantially as described.

11. A weed guard for an outboard motor having a housing and a propeller supported thereby, comprising the combination with a mounting bracket for connection with said housing, of a weed guard connected with the bracket for support in a propeller guarding position and comprising a pair of blades connected together in substantial parallelism at their upper ends and divergent downwardly and rearwardly before the propeller, the divergent lower ends of the blades being provided with sharp weed cutting edges.
